[57] ABSTRACT

A machine for precise cutting of the collated pages of an unbound book has a conveyor with clamps for carrying successive books along a line past two oppositely rotating cutting wheels or precision saws which cut into the book from opposite sides of the book line. Each wheel has a plurality of identical cutting inserts or bits interchangeably fitting in sockets on the wheels. Each bit has four cutting corners or points two of which are effective on each wheel.

PRECISION BOOK CUTTING APPARATUS

BACKGROUND OF THE INVENTION

As set forth in United States patent application Ser. No. 165,273, filed July 22, 1971 by Richard H. Barbour, Jr. for Method of Cutting Thick Books, now U.S. Pat. No. 3,726,167 and incorporated herein by reference, a great improvement in cutting collated books prior to binding is obtained by penetrating the outer face of the book with a bevelled, chisel-like cutting edge and with the outer extremity of the cutting edge entering first and penetrating deeper than the rotationally forward extremity of the same edge. This new use of the bevelled cutting edge produces a cut of the highest quality and excellent salvageable scrap with avoidance of dust and confetti, all with a remarkable reduction in power consumption as compared with known prior book cutting methods. The new method may be employed in the Cutter for Book Binding disclosed in U.S. Pat. No. 3,570,350 of Robert E. Fogg, issued Mar. 16, 1971, also incorporated herein by reference, with the further advantage of reducing the pressure required to clamp the book pages during cutting and of avoiding damage to the book during cutting.

The object of the present invention is to provide book cutting wheels with replaceable cutting inserts or bits with cutting edges particularly adapted to take advantage of the above described book cutting method of Richard H. Barbour, Jr. as applied to the book cutting apparatus of Robert E. Fogg, and produce a book cut of improved precision.

STATEMENT OF INVENTION

According to the invention apparatus for precision cutting of a book comprises means for conveying successive books on a line, two successive cutting stations on opposite sides of the line, oppositely rotating cutting wheels at said stations for cutting into opposite sides of the books, the wheels having a plurality of sockets in one surface aligned in directions respectively inclined to the wheel axis in one of the opposite directions of rotation; a plurality of cutting bits respectively received in the sockets, the bits having an end cutting edge normal to the inclination of the socket providing radially inner and outer cutting points at each end of each edge, and the wheels being disposed with respect to the book so that the outer cutting point penetrates and cuts the book, and means to mount each bit in the sockets of either wheel interchangeably so that the unused inner point on one wheel is disposed as the outer point on the oppositely rotating wheel.

DRAWINGS

FIG. 1 is an isometric view of book cutting apparatus employing two counter rotating cutting wheels;

FIG. 2 is an enlarged fragmentary plan view of one wheel showing the location of cutting bits thereon;

FIGS. 3, 4 and 5 are respectively plan, side and end views of a bit; and

FIGS. 6 and 7 are sections respectively on lines 6—6 and 7—7 of FIG. 2.

DESCRIPTION

Shown in FIG. 1 is book cutting apparatus comprising a conveyor 1 from which are supported spaced pairs of clamps 2, each pair holding the unbound col-

lated pages of a book B. The conveyor moves the books in the direction of the arrow 1* through two cutting stations 3 and 4. At the first station 3, a cutting wheel 6, driven clockwise by a motor 7 cuts into the near face 5 of the book and partway through its lower edge or backbone above the signature folds. At the second station 4, an oppositely rotating wheel 8 driven by a counterclockwise rotating motor 9 cuts into the far side of the book completing the previous cut. As described in 10 the aforementioned Fogg U.S. Pat. No. 3,570,350, making two cuts shallower than one complete cut substantially reduces the book clamping force and the possibility of wrinkling or otherwise damaging the book by the greater saw force required for a complete cut. In 15 two cut apparatus, however, it is necessary that the teeth of the cutting wheel be inclined or raked in opposite directions. While some cutting wheels may be inverted to present oppositely inclined teeth, if the teeth are joined integrally with the wheel by brazing or welding, the wheel as a whole must be removed for resharpening or discarded when the teeth are dulled. Prior replaceable inserts or bits, well known in the metal machining art, are not suitable for practising the method of the Barbour patent application Ser. No. 165,273.

20 Shown in FIGS. 2, 6 and 7 is the clockwise rotating wheel 6. The counter clockwise rotating wheel 8 is the mirror image of wheel 6. Wheel 6 has a disk shaped body 11 in whose upper face are a number (e.g. 10) of spaced sockets 12 opening at the periphery of the 25 wheel for receiving a cutting insert or bit 15. Adjacent and opening on each socket is a recess 13. Staked centrally in each socket is a register pin 14 fitting an aperture 16 in the bit 15. A central bore 17 in each recess is threaded to receive a machine screw 20 for securing a bit block 18 in the recess 13.

The cutting bit 15 has two cutting edges 19 formed at its ends by undercut bevelled faces 21. Overcut lateral bevelled edges 22 fit respectively in the socket 12 and under a bevelled edge 23 of the clamping block 18 so that when the screw 20 is tightened on the block 13 the bit 15 is securely wedged in the socket 12. The lateral bevels of the bit may be modified if other known bit clamping means are used.

According to the Barbour application, Ser. No. 165,273, markedly improved quality of book cut and salvageable scrap, lower equipment cost and economy of power are realized, if the cutting edge 19 of the bit at the point of entry into the book is inclined at an angle of 0° to 20° away from the face plane of the book, and the outer, rotationally rearward extremity or cutting point 24 (as compared to the inner point 26) enters the page first and penetrates deepest. Such conditions are met if the cutting edge is inclined at 45° to the radius of a 9 inch wheel making a cut of 1-1/4 inch depth. In use the inner point or extremity 26 of the cutting edges does little or no cutting and does not dull appreciably, whereas the outer extremity 24 does the cutting and wears or dulls by fracture.

By extending the end bevel 21 entirely along a cutting edge 19 normal, i.e., at right angles, to the longitudinal axis of the bit, the bit with a normally unused extremity 26 which is inward on the clockwise rotating wheel 6 may be removed and inserted in the counterclockwise rotating wheel 8 where it becomes the outer active cutting point of the bit. Such bit construction doubles the useful life of the bit. Moreover by providing a like, normal cutting edge 19* symmetrical with

the first edge 19 at the other end of the bit, two additional cutting points 24* and 26* are provided. The additional cutting points 24* and 26* are respectively useful on oppositely rotating cutting wheels, thus quadrupling the useful life of the bit. The additional cutting point 24* being diametrically disposed with respect to cutting point 24 may be reversibly disposed in a wheel of the same direction of rotation and at the same radial distance on the wheel.

It should be understood that the present disclosure is for the purpose of illustration only and that this invention includes all modifications and equivalents which fall within the scope of the appended claims.

I claim:

1. Apparatus for precision cutting of a book comprising:
 means for conveying successive books on a line, 15
 two successive cutting stations on opposite sides of the line,
 oppositely rotating cutting wheels at said stations for 20
 cutting into opposite sides of the books, the wheels having a plurality of sockets in one surface aligned in directions respectively inclined to the wheel axis in one of the opposite directions of rotation,
 a plurality of cutting bits respectively received in the 25
 sockets, the bits having an end cutting edge normal to the inclination of the socket providing radially inner and outer cutting points at each end of each edge, and the wheels being disposed with respect to the book so that the outer cutting point penetrates 30
 and cuts the book first, and
 means to mount each bit in the sockets of either wheel interchangeably so that the unused inner point on one wheel is disposed as the outer point on the oppositely rotating wheel.

10

30
35

2. Apparatus according to claim 1 wherein each bit cutting edge is defined by a plane surface parallel to the planes of the wheel.

3. Apparatus according to claim 2 wherein the cutting edge is further defined by a face inclined from the plane surface toward the wheel.

4. Apparatus according to claim 1 wherein each bit has an identical cutting edge at its other end, thereby to provide four cutting points on each bit.

5. Apparatus for precision cutting of a book comprising:

means for conveying books on a line;
 a cutting wheel adjacent to the line for cutting into the sides of the books, the wheel having a plurality of spaced sockets in one plane surface aligned in directions respectively inclined to the direction of rotation of the wheel;
 a plurality of cutting bits respectively fitting in the sockets, each bit having a longitudinal axis of symmetry and two bevelled cutting edges symmetrically disposed with respect to the axis, the two cutting edges terminating in diametrically disposed cutting points, and
 means detachably holding the bits in the wheel sockets with either cutting point of each bit disposed at the same radial distance on the wheel so that the bits may be reversed in the sockets to use either cutting point.

6. Apparatus according to claim 5 wherein the cutting edges of the bits are normal to the bit axis.

7. Apparatus according to claim 5 wherein each bit has oppositely extending longitudinal surfaces parallel to the bit axis, and said sockets and holding means have overlying surfaces engaging the bit surfaces.
